UNITED STATES PATENT OFFICE.

HENDRIK DE CLERCQ, OF AMSTERDAM, NETHERLANDS.

PRINTING-MACHINE.

1,324,771.

Specification of Letters Patent.

Patented Dec. 9, 1919.

Application filed September 20, 1919. Serial No. 325,235.

To all whom it may concern:

Be it known that I, HENDRIK DE CLERCQ, a subject of the Queen of the Netherlands, residing at Amsterdam, Netherlands, have 5 invented certain new and useful Improvements in Printing-Machines, of which the following is a specification.

In addressographs, the printing is effected by relief forms which by suitable means are 10 pressed on the sheet to be printed, during which operation an ink ribbon is located between the form and the sheet. This arrangement entails a comparatively considerable power consumption and has the further objectionable feature that the forms are very 15 liable to damage; moreover the presence of an ink ribbon between the form and the sheet during the impression causes the ink to be pressed out of the ribbon and the latter 20 to be subjected to rapid wear and tear.

According to my present invention, which has for its object to obviate the above inconveniences, the form and the sheet to be printed are simultaneously fed between two members 25 rolling the one on the other, during which operation said members exert a certain amount of pressure on one another.

The annexed drawing serves to illustrate my invention; in this drawing:

30 Figures 1 and 2 are a somewhat diagrammatic side view, and bottom view respectively, of one embodiment of my invention, and

35 Figs. 3 and 4 are a side elevational view, and top view respectively, of a second embodiment.

In Figs. 1 and 2, the reference numerals 1 and 2 designate two cylinders located the one vertically above the other. The top 40 cylinder is rotatable about a spring loaded shaft, and by adjusting the tension of said spring the pressure between both cylinders may be regulated to suit the demand of the work in a manner well-known in the art.

45 The lower cylinder 2 is mounted on a shaft 3, and keyed on this shaft is a miter wheel 4 meshing with a miter wheel 5 on a manually or motor driven shaft 6. In practice, the shaft 6 is coupled with a mechanism 50 for feeding the forms in a continuous series to the impression cylinders 1 and 2.

The printing forms are fed in a continuous series along guide bars 7 and 8 extending along the sides of the cylinders and arranged 55 adjacent the meeting point of the impression cylinders 1 and 2. By means of suitable

mechanism, or in some cases manually, a sheet of paper or other suitable material is fed between the cylinders 1 and 2 together with the form whereby the text of the form 60 is impressed on the sheet.

Ordinarily the forms may be inked before being fed between the impression cylinders 1, 2, but in some cases the inking of the forms may be dispensed with, when the text 65 is simply pressed in relief into the sheet; as a matter of course the impression in this case requires a comparatively great pressure between the cylinders 1, 2.

The mechanism shown in Figs. 3 and 4 70 comprises two stationary guide bars 9, 10 for the flat printing forms which by suitable means (not illustrated) are moved in a continuous series therealong. Mounted at some vertical distance above said bars 9, 75 10 is a flat impression block 11 connected at 13, by a rod 12 with the frame of the machine. The rod 12 is composed of two parts adapted to be secured together to form a rod of adjustable length whereby 80 the position of the block 11 relative the guide bars 9, 10 may be changed.

Vertically below the bars 9, 10 are rails 14, 15 supporting wheels 16, 17 loosely mounted on the axis 18 of an impression 85 cylinder 29. The shaft 18 is supported in bearings provided in a strap 19 pivoted to a crank 20 from which it receives reciprocating motion. The strap 19 is of two-part formation in the same manner as rod 12, 90 whereby its length may be adjusted to suit the position of the block 11.

Springs 21, 22 tend to press the wheels 16, 17 against collars on shaft 18 and said wheels have freedom of axial movement on 95 shaft 18 against the action of the springs 21, 22. An axial displacement of the wheels is caused by the extended hubs 23, 24 of the wheels, when moving to the left, engaging guide members 25, 26 on the rails 100 14, 15, whereby the wheels move toward one another so as to disengage their rails, and the strap 18 with the parts associated therewith moves downward by gravity until the extended hubs 23, 24 are received by 105 the rails 14, 15. If now the shaft 18 moves to the right, the wheels 16, 17, after a certain horizontal movement, reach inclined tracks 27, 28 which elevate the running surfaces of the wheels back to the level of 110 the rails 14, 15, at which time the wheels are pressed apart by the springs 21, 22, so

that from that moment onward they again roll normally on said rails.

The arrangement is such that the curved surface of cylinder 29 is at a very small distance from the impression block 11 during its movement to the left, that is to say during the time wherein the shaft 18 assumes its highest position, so that the printing operation may be effected between the stationary block 11 and the moving cylinder 29. For this purpose a relief printing form, together with the sheet to be printed, is manually or mechanically fed below the impression block 11 the moment wherein, or before, the cylinder 29 begins to move to the left. When the printing operation is finished, the cylinder 29 descends by gravity so that it moves at some considerable vertical distance from the block 11 during its movement to the right, when the form and the sheet, or only the sheet as the case may be, may be removed and replaced.

In order to avoid damage to the sheet and to the form, the members rolling the one on the other, that is to say the block 11 and the cylinder 29, may be covered with suitable resilient material such as rubber or a sheet of rubber may be fed between said members together with the sheet to be printed and the form.

As a matter of course my invention may be applied both with low and with high relief forms.

35 What I claim as my invention is:

1. In mechanism of the character described, a flat impression block and a reciprocable impression cylinder whose shaft during its movement in the one direction is at a greater distance from the block than during its movement in the reverse direc-

tion, in combination with wheels loosely mounted on the shaft of the impression cylinder, springs tending to force the said wheels apart, rails for guiding the wheels, slanting surfaces adapted at the end of the movement of the impression cylinder in the one direction to push the wheels toward one another so as to cause their running surfaces to disengage the rails and concentric cylindrical wheel portions of smaller diameter resting on the rails and inclined surfaces adapted at the end of the reverse motion of the impression cylinder to bring the wheels back to their original level. 55

2. A mechanism of the class described comprising a plurality of parallel rails adapted to support a printing form, a pressure block adapted to exert pressure upon said form, a plurality of rails located below the first rails and spaced apart, a bracket, a shaft supported by said bracket, a cylinder carried by said shaft, a roller mounted on said shaft on each side of the cylinder and having an outwardly extending boss, resilient means pressing the rollers away from said cylinder, guide members carried by the rails and adapted to engage the bosses of the rollers when the shaft is moved in one direction for causing the rollers to move toward the cylinder and disengage the lower rails, inclined tracks adapted to be engaged by the rollers when the shaft is moved in the opposite direction for raising the rollers to a point sufficiently 75 high so that said rollers will engage the lower rails, and means for reciprocating said bracket.

In testimony whereof I affix my signature.

HENDRIK DE CLERCQ.
